(57) **CLAIM**

The ornamental design for a wall for store within store, as shown and described.

DESCRIPTION

FIG. 1 is a perspective view of a wall for store within store according to a first embodiment of our new design; FIG. 2 is a perspective view of the design of FIG. 1 shown rotated 180 degrees;

FIG. 3 is a top view of the design of FIG. 1;

FIG. 4 is a front side view of the design of FIG. 1;

FIG. 5 is a rear side view of the design of FIG. 1;

FIG. 6 is a left side view of the design of FIG. 1;

FIG. 7 is a right side view of the design of FIG. 1; and, FIG. 8 is a perspective view of a second embodiment of our new design which differs from the first embodiment in having contrasting material on a top surface of the facing walls.

The dash-dash broken lines illustrate environmental structure and form no part of the claimed design.

The curved dash-dot-dash broken-away lines indicate break lines and the appearance of any portion of the article on or between the break lines forms no part of the claimed design.
